Primary Examiner—Ralf Seifert**Attorney, Agent, or Firm**—Finnegan, Henderson, Farabow, Garrett & Dunner, L.L.P.**[57] CLAIM**

The ornamental design for an advertising carrying body for use on a filler gun, as shown and described.

DESCRIPTION

FIG. 1 is a top plan view of an advertising carrying body for use on a filler gun showing my new design;

FIG. 2 is a front perspective view from above and other side of the carrying body;

FIG. 3 is a side view from one side of the carrying body;

FIG. 4 is a side view from other side of the carrying body;

FIG. 5 is a front perspective view from above and other side of the carrying body;

FIG. 6 is a rear perspective view from below and from other side of the carrying body;

FIG. 7 is a rear perspective view from above and other side of the carrying body;

FIG. 8 is a rear perspective view from above and one side of the carrying body;

FIG. 9 is a view from above of the carrying body;

FIG. 10 is a view from below of the carrying body;

FIG. 11 is a front view of the carrying body;

FIG. 12 is a rear view of the carrying body;

FIG. 13 is a front perspective view from above and one side of a top member embodying part of my new design and forming a lid part of the carrying body;

FIG. 14 is a top view of the top member;

FIG. 15 is a bottom view of the top member;

FIG. 16 is a view from one side of the top member;

FIG. 17 is a view from other side of the top member;

FIG. 18 is a rear view of the top member; and,

FIG. 19 is a front view of the top member.
